UNITED STATES PATENT OFFICE.

JOSEPH ASKINS, OF RIDGEFIELD, NEW JERSEY.

DESIGN FOR A TIRE.

SPECIFICATION forming part of Design No. 27,922, dated November 30, 1897.

Application filed October 7, 1897. Serial No. 654,469. Term of patent 14 years.

To all whom it may concern:

Be it known that I, JOSEPH ASKINS, a citizen of the United States, residing at Ridgefield, in the county of Bergen and State of New Jersey, have invented or produced a new and original Design for Pneumatic Wheel-Tires, of which the following is a specification.

The object of this design is to provide a novel pneumatic wheel-tire which presents an ornamental and characteristic appearance to the eye; and the leading feature of the design consists in a pneumatic wheel-tire circular in cross-section and having at the tread portion sloping lines merging into a convex surface to produce a substantially segmental projection extending entirely around the periphery of the tire in a plane coincident with a diametrical line taken vertically through the tire.

The design is illustrated by the accompanying drawings, in which—

Figure 1 is an edge view of my new form or shape of pneumatic wheel-tire. Fig. 2 is a transverse sectional view of the same.

In the drawings the numeral 1 indicates the body of the tire, which is circular in cross-section when inflated; 2, the sloping lines

merging into the convex surface 3, by which a segmental projection is formed on the tread portion of the tire entirely around its circumference in a plane coincident with a line drawn vertically through the tire when in use. The sloping lines 2 and the convex surface 3 and the particular location of these parts relatively to the plane drawn vertically through the tire impart to the latter a novel and ornamental appearance and provide a pneumatic wheel-tire of rubber which presents a characteristic and peculiar appearance to the eye. The convex projection arranged as shown is an integral part of the tire itself, and the lines are so curved as to present a neat and symmetrical contour.

What I claim is—

The design for a pneumatic wheel-tire substantially as shown and described.

In testimony whereof I have hereunto set my hand in presence of two subscribing witnesses.

JOSEPH ASKINS.
